UNITED STATES PATENT OFFICE.

JACOB LUTER, OF BAYONNE, NEW JERSEY.

KEY-OPERATED LOCK.

1,290,612.

Specification of Letters Patent. Patented Jan. 7, 1919.

Application filed October 22, 1917. Serial No. 197,755.

To all whom it may concern:

Be it known that I, JACOB LUTER, a citizen of the United States, and resident of Bayonne, in the county of Hudson and State of New Jersey, have invented certain new and useful Improvements in Key-Operated Locks, of which the following is a specification.

This invention relates to a key operated lock. Its organization comprises a key with a hollow post having a pin which engages a movable spindle in a key post. The latter transmits its movements to a locking pin that unlocks a tumbler in the lock. The said tumbler is normally locked with a combined latch and locking bolt. The latter can be located in three positions as follows: An inward position in which the lock is open, an intermediate position in which it performs the office of a latch and an outward position when the lock locks the appurtenances to which it is connected.

Figure 1 represents a front elevation of one embodiment of the lock with its latch and locking bolt in its intermediate position; Fig. 2 shows a right hand side view of Fig. 1; Fig. 3 is a rear view of Fig. 1 with a portion broken away; Fig. 4 is a partial section of Fig. 3 on the line 4, 4; Fig. 5 is a view similar to Fig. 3 with a guard plate thereof removed; Fig. 6 shows a section of Fig. 3 on the line 6, 6; Fig. 7 is a view similar to Fig. 5 with a number of elements removed; Fig. 8 shows a top plan view of one of the elements of Fig. 7; Fig. 9 represents a section of Fig. 7 on the line 9, 9; Fig. 10 is a view similar to Fig. 5 with its latch and locking bolt in its outward position; Fig. 11 is a view similar to Fig. 10 with its latch and locking bolt in its inward position; Fig. 12 is a top plan view of the latch and locking bolt of the lock; Fig. 13 represents a partial enlarged section of Fig. 10 on the line 13, 13; Fig. 14 shows an enlarged section of Fig. 10 on the line 14, 14; Fig. 15 is a partial left hand side view of Fig. 14; Fig. 16 shows an enlarged section and side view on the line 16, 16 of Fig. 10; Fig. 17 shows an elevation of the lock attached to a door and its accompanying socket attached to a door jamb, and Fig. 18 is a top plan view of Fig. 17.

The lock is shown with a casing comprising the main wall 20, side walls 21, 22, top wall 23 and bottom wall 24. The edges 55 of the walls 22, 23 and 24 have formed therewith flanges 25 and strengthening posts 26

extend between the inner face of the wall 20 and the flanges 25. A guide opening 27 is formed in the wall 21 for the bolt to be described. A pin 30 extends from the inner 60 face of the wall 20 and has hinged thereon a tumbler designated in its entirety by the letter A.

The latch A comprises the barrel 31 from which extends the upper member 32 having 65 formed therewith the heel 33, the lower member 34 and the side members 35 and 36 which connect the members 32 and 34. A stop pin 39 extends up from the wall 20 and the member 34 bears against said pin when the 70 tumbler A is in its normally horizontal position. A spring 40 has one end thereof fastened to the member 32 by means of the screw 41 and its other end bears against one of the posts 26 and tends to locate the tumbler 75 A in its normally horizontal position. From the inner face of the wall extends a guide post 45 which is shouldered at 46 to form the supporting tables 47 for the supporting guide plate 48. A boss 49 extends 80 from the inner face of the wall 20 which has journaled therein the pin 50, and at one end of the latter is fastened the pinion 51 and at its other end is fastened the operating knob 52 by means of the screw 53. Posts 85 57, 58, 59 extend up from the inner face of the wall 20 and separator sleeves 60 encircle the latter posts. A guard plate 61 has openings to permit the posts 57, 58 and 59 to extend therethrough. The guard plate bears 90 on the sleeves 60 and screws 62 bear on the plate and clamp the said guard plate in place. A tubular guide 63 with the longitudinal slot 64 extends from the guard plate 61. A guide notch 65 is formed in the 95 plate 61.

A second guard plate is indicated at 66 and is secured to the wall 20 by means of the screws 67 and 68. Pins 70 and 71 extend from the guard plate 66 and a spring 100 with the arms 72 and 73 is supported on the pin 70.

A combined latch and locking bolt is indicated in its entirety by the letter B and comprises the outer portion 75 with the tapered end 76, and the inner portion 77. To the inner face of the portion 77 are fastened the teeth 78 which can mesh with the pinion 51. The portion 75 bears on the inner face of the wall 20 and the portion 77 bears on 110 the guide plate 48. A guide slot 80 is formed in the portion 77 and forms a guide

for the guide post 45. An elongated indent 81 and an indent 82 are formed in the upper edge of the portion 77. An indent 85 and the indents 87 and 88 with their accompanying tooth 89 are formed in the lower edge of the portion 77. The indent 88 is curved as shown at 90 and extends to its accompanying end of the portion 77. A pin 91 extends up from the portion 77 and the 10 arm 72 can bear against the same. A spring 92 has one end thereof fastened to the portion 77 by means of the screws 93. A pin 95 extends from the portion 77 and has pivoted thereto the pawl 96 with the curved 15 lower end 97 and heel 98. The spring 92 bears on the upper surface of the pawl 96. The outer surface of the portion 75 of the latch and locking bolt and the outer edge of the spring 92 bear against the inner face of the 20 guard plate 61.

From the inner face of the wall 20 extends the tubular key post 100 with the contracted openings 101 and 102 at its ends. The seats 103 and 104 are formed in the post. A 25 plunger 110 is slidably located in the key post 100 and has extending from one end the long spindle 111 and from the other end the spindle 112. A spring 113 encircles the long spindle 111 and bears between the seat 103 and the accompanying end face of the plunger 100, to normally maintain the end of the long spindle 111 in line with the outer face of the wall 20 and the outer end of the spindle 112 outside of the end of the key 30 post 100. From the outer face of the wall 20 extend a pair of screw guide posts 115, 116. A follower plate 117 is slidably supported on the posts 115 and 116. A guide pin 118 extends from the plate 117. A 35 locking plate 119 having a locking pin 120, normally bears against the outer face of the wall 20 and the outer end of the long spindle 111, and has an opening at one end which engages the post 116. An opening 121 is 40 formed in the plate 119 for the pin 118. A spring 122 encircles the pin 118 and bears between the plates 117 and 119. The locking pin 120 locks the member 34 of the latch A when it is in its normal horizontal position. 45 A locking cover is indicated at 125 which bears against the outer face of the wall 20. A locking bracket is indicated in its entirety at C and which comprises a barrel 126, from which extends at one side the locking pin 50 127 which coacts with the indent 85 of the portion 77 of the bolt of the lock. From the other side of the barrel 126 extends the leg 128 with the slot 129. A bolt with the head 130 is located in the barrel 126. The bolt 55 has formed therewith the shouldered portion 130^a and the threaded end 131. The shouldered portion 130^a can move in an elongated opening 132 formed in the wall 20. The threaded end 131 engages a threaded opening 60 135 in the cover 125. A spring washer 133

is located between the head 130 and the top face of the barrel 126. A screw 135 is shown with the enlarged portion 136. The screw 135 engages a threaded opening in the cover 125 and the portion 136 is located in an elongated opening 137 in the cover. A screw 138 in the wall 20 has an enlarged portion 139 engaging the slot 129. 70

A key is shown with the hollow stem 140 having the pin 141 in the axial center thereof. The bit 142 of the key is shown with the narrowed portion 143. Openings 144 are made in the stem 140 adjacent to the pin 141 to prevent foreign matter clogging up the stem. Upon the guard plate 61 is pivoted a locking arm 145 which has extending therefrom a locking pin 146 that passes through an opening 147 in the guard plate 61 and extends to nearly the outer face of the portion 77 of the latch and bolt. An 80 arm with the legs 148 and 149 is pivoted to the outer face of the guard plate 61. The upper edge of the leg 148 bears against the lower edge of the arm 145. A pin 150 extends from the guard plate 61 and supports 85 a spring with the arms 151 and 152. The arm 151 bears against the top edge of the arm 145 and the arm 152 bears against the leg 149. A cover 155 with the key opening 90 156 is secured to the guide plate 61 by means 95 of the screws 157.

Referring to Figs. 17 and 18 the lock is shown attached to the inside face of a door 158 and the portion 75 of the combined bolt and latch is seated in the socket 159 secured 100 to the door jamb 160. The lock is fastened to the door by means of the screws 164 and the socket 159 is fastened to the jamb 160 by means of the screws 165.

To operate the lock the parts may be considered located as shown particularly in Figs. 1, 2, 3, and 5 with the combined latch and bolt having the portions 75 and 77 in its intermediate position. The said latch and bolt can in this position be drawn into the lock by means of the knob 52, because the pinion 51 is in mesh with the teeth 78, and the heel 33 is located at the inward end of the indent 81, and then locked in that position by pushing up the locking cover 125 115 which causes the locking pin 127 to lock with the indent 85. When the pin 127 is disengaged from the indent 85, the tension of the spring having the arms 72, 73 will force the latch and locking bolt having the portions 110 75 and 77 to assume the positions shown in Figs. 1, 2, 3 and 5. To locate the said latch and locking bolt in its outward position, the key of the lock is located with its stem 140 encircling the key post 100 and pressure is 120 brought on the key to engage the pin 141 with the spindle 112 and move the latter, so that the long spindle 111 will raise the locking plate 119 and thereby raise the locking pin 120, so that its outer end will move to 125 130

the inner face of the wall 20. The key is then turned in the direction of the arrow D so that the heel 33 is disengaged from the indent 81 and forces the combined latch and locking bolt to its outward position to lock the door 158 with the jamb 160. The key is turned to make a second revolution in the same direction, and the bit 142 in this second revolution engages the curved lower end 97 of the pawl 96, until it is brought to the position shown in Fig. 10 with the locking pin 146 bearing against the lower face of the heel 98 of said pawl. The operator then again turns the key in the same direction D until the bit 142 strikes the leg 149, which raises and disengages the pin 146 from the heel 98 and allows the pawl 96 and the tumbler A to spring to its normal position, as shown in Fig. 5, but with the combined latch and locking bolt in its outward position and the heel 33 locked with the indent 82. The lock is now securely located in its outward or locked position. To open the lock the key is again pressed down and turned in a direction opposite to the arrow D and the bit 142 will engage the face F of the pawl 96 and the narrowed portion 143 will again engage the member 34 of the tumbler A, and move the combined latch and locking bolt having the portions 75 and 77 to the positions shown in Fig. 5. The key can now be withdrawn. If it is desired to move the latch to its inward position with the key the latter is again turned in a direction opposite to the arrow D and the bit 142 is made to bear against the face G of the tooth 89, and the narrowed portion 143 against the member 34 of the tumbler A as shown in Fig. 11 and the pin 127 is forced up to lock with the indent 85.

Having described my invention what I desire to secure by Letters Patent and claim is:

45 1. In a lock the combination of a combined latch and locking bolt having indents for engagement with the bit of a key, a tumbler coacting with the combined latch and locking bolt and adapted to lock therewith, and a locking pin normally locking with the tumbler, the said key adapted to disengage the locking pin from the tumbler and unlocking the latter from the latch and locking bolt.

2. In a lock the combination of a latch and locking bolt, a tumbler normally locking with the latch and locking bolt, a locking pin normally locking the tumbler in position, a key post for the lock coacting with a key to disengage the locking pin from the tumbler, the said key swinging the tumbler out of its path and moving the latch and locking bolt.

60 3. In a lock the combination of a combined latch and locking bolt having indents; a tumbler normally locking with the latch

and locking bolt, a locking pin normally locking the tumbler in position, and a key to unlock the locking pin from the tumbler and to unlock the tumbler from the latch and locking bolt and move the latter.

70

4. In a lock the combination of a casing, a tumbler with an upper and a lower member hinged in the casing, a stationary stop pin for the lower edge of the lower member and a movable locking pin for the upper edge of said lower member.

75

5. In a lock the combination of a casing, a tumbler with an upper and a lower member hinged in the casing, a stationary stop pin for the lower edge of the lower member, a movable locking pin for the upper edge of said lower member and a spring to force the lower member against its stationary stop.

80

6. In a lock the combination of a casing, a tumbler hinged therein, a tubular key post for the casing, a movable spindle in the key post adapted to be actuated by a key and a spring actuated locking plate normally bearing on the outside case of a wall of the lock and having a locking pin extending through said wall in the path of said tumbler, the locking plate being in the path of the movable spindle of the key post.

85

7. In a lock the combination of a casing, a tubular key post extending from the casing, a spring actuated plunger in the key post, a spindle extending from each end of the plunger, a locking plate with a locking pin actuated by the outer end of one of said spindles, a tumbler in the casing coacting with the locking pin and a key coacting with the outer end of the other spindle.

90

8. In a lock the combination of a casing, a tubular key post extending from the casing, a spring actuated plunger in the casing, a spindle extending from each end of the plunger, one of said plungers normally extending to the outer surface of a wall of the casing and the spindle at the other end of the plunger normally extending out of the key post, and a tubular key with a pin therein for the lock, the pin of the key coacting with the pin of the key post that normally extends out of the same, to force the plunger down in the key post and force the other spindle out of the wall of the lock.

105

9. In a lock the combination of a combined latch and locking bolt, a pawl pivoted to the latch and locking bolt, a spring with one end fastened to the latch and locking bolt and the other end thereof bearing on the pawl, a locking arm with a locking pin pivoted in the lock, the said pin engaging the said pawl in a predetermined position thereof and means to disengage the locking pin from the pawl.

110

10. In a lock the combination of a combined latch and locking bolt, a pawl pivoted to the latch and locking bolt, a spring with one end fastened to the latch and locking

120

125

130

bolt and the other end thereof bearing on the pawl, a locking arm with a locking pin pivoted in the lock, an arm with a pair of legs pivoted in the lock, the edge of one of 5 said arms contacting with the edge of the locking arm, a tubular guide for a key for the lock, one of the edges of said other leg normally bearing against said guide, a spring having a pair of arms with one of 10 said arms bearing against the locking arm and the other arm of the spring bearing against the leg that bears against the tubular guide and a key to move the latter leg.

11. In a lock the combination of a casing, 15 a combined latch and locking bolt having an indent, the said latch and locking bolt slidably located in said casing, an adjustable locking bracket coacting with said latch and locking bolt, said bracket comprising a barrel, a screw extending through said barrel and through an elongated opening in the casing, a locking cover engaging the threaded end of the screw outside of the casing, a locking pin extending from the bracket 20 adapted to lock with the indent in the combined latch and locking bolt and a spring washer between the head of said screw and said barrel.

12. In a lock the combination of a casing, 30 a combined latch and locking bolt having an indent slidably located in said casing, a slideable locking cover on the outer faces of the casing, a locking bracket on the inside of the casing with a portion thereof extending 35 through an elongated opening in the casing and connected to the locking cover, a locking pin on said bracket adapted to lock with the indent of the combined latch and locking bolt and a screw extending through 40 an elongated opening in the casing with its head on the inside of the casing and its

threaded end in engagement with said locking cover.

13. In a lock the combination of a casing, 45 a combined latch and locking bolt slidably located in the casing, a guard plate in the casing over the said combined latch and locking bolt, a tubular guide for a key extending from an opening in said guard plate, an arm with a pair of legs pivoted to 50 the guard plate with one of its legs normally bearing against the tubular guide, a pawl pivoted to the combined latch and locking bolt, a locking arm having a locking pin pivoted to the guard plate and normally bearing against the other leg of said 55 arm and a spring with the central portion engaged by a pin on the guard plate, and having a pair of arms one of the arms of the spring bearing against one of the legs of 60 the arm having two legs and the other arm of the spring bearing against the locking arm, the locking pin of the said locking arm adapted to engage said pawl.

14. In a lock the combination of a casing, 65 a locking arm with a locking pin pivoted therein, an arm with a pair of legs pivoted in the casing, and a spring with its central portion engaged by a pin in the casing and having a pair of arms, one of the arms of 70 the spring bearing on the locking arm and the other arm of the spring bearing on one of the legs of the arm having the pair of legs.

Signed at Bayonne, in the county of Hudson and State of New Jersey, this 15th day of October A. D. 1917. 75

JACOB LUTER.
